Filed Aug. 27, 1962, Ser. No. 71,455

Term of patent 14 years

(Cl. D59—6)

The figure is a plan view of a check showing my new design.

The essential features of my design reside in the portions shown in full lines and more specifically in a check having a background of horizontal lines broken at irregular intervals by substantially square-shaped figures printed thereon and having a specific border and shaded areas all as shown.

I claim:

The ornamental design for a check, as shown and described.
